UNITED STATES PATENT OFFICE.

WALTER WILLIAM PHILLIPS, OF LONDON, ENGLAND.

DESIGN FOR A HEEL PAD FOR A BOOT OR SHOE.

Application filed August 8, 1922. Serial No. 3,313. Term of patent 14 years.

To all whom it may concern:

Be it known that I, WALTER WILLIAM PHILLIPS, a subject of the King of Great Britain and Ireland, residing at London, England, have invented a new, original, and ornamental Design for a Heel Pad for a Boot or Shoe, of which the following is a specification, reference being had to the accompanying drawings, forming part thereof.

The figure is a view of the underside or wearing surface of a heel pad for a boot or shoe, showing my new design therefor.

I claim:

The ornamental design for a heel pad for a boot or shoe, as shown.

Signed at London, England, this 28th day of July, 1922.

WALTER WILLIAM PHILLIPS.
